EXHALATORY CONTROLLER FOR
INHALERS

Harold V. O'Connell, New York, N. Y.

Application May 9, 1934, Serial No. 724,792

4 Claims. (Cl. 128—140)

This invention relates to exhalatory controllers for nasal inhalers and the like, and has for an object the provision of an exhalatory controller which will enable an anaesthetist more accurately to determine and control the patient's state of anaesthesia.

In administering an anaesthetic, such as nitrous oxide, a small mask or hood, commonly known as an inhaler, suitably connected with anaesthetic and oxygen tanks, is placed over the nose of the patient. The patient, accordingly inhales the mixture of anaesthetic and oxygen which comes from the tanks. The exhalant, however, escapes through an outlet passage or exhalatory formed in the inhaler, and provided with a one-way valve so as to permit gas to escape from the inhaler mask when a sufficient pressure exists in the mask, but preventing air and other outside gases from entering into the mask. Considerable difficulty has been experienced by anaesthetists in administering anaesthetics in this manner, due to the fact that the patient's state of anaesthesia can be most accurately determined by the strength and rhythm of his respiration, and an inhaler mask muffles the sound of the respiration rendering it exceedingly difficult, if not impossible, for the anaesthetist to observe it. The exhaling valves heretofore provided have also caused considerable difficulty in that they sometimes stick or jam and at other times permit leakage or back flow of air, and furthermore, they have not been subject to the sensitive and accurate adjustment necessary to properly control the patient's state of anaesthesia.

It is accordingly an object of this invention to provide an exhalatory controller having a sound producing chamber or whistle operated by the exhalant passing through the controller so that the anaesthetist may at all times be aware of the strength and rhythm of the respiration, and provided with an improved valve which will not stick, jam, or permit leakage or back flow of air, and which may be sensitively adjusted so as to permit the anaesthetist to control more accurately the patient's state of anaesthesia.

For a fuller understanding of the invention reference should be had to the accompanying drawing, in which

Figure 1 is a side elevation of an exhalatory controller embodying features of my invention and illustrated as applied to an inhaler of conventional construction;

Fig. 2 is an elevation in section of the exhalatory controller showing a portion of the inhaler mask to which it is applied, and

Fig. 3 is a cross section taken in the direction of the arrows on the line 3—3 of Fig. 2.

In the accompanying drawing, the improved exhalatory controller is illustrated as applied to an inhaler 4 of conventional design, comprising a rubber mask or hood 2 designed to fit over a patient's nose, resting on his upper lip and on the bridge and both sides of his nose, and having suitable connection with an anaesthetic supply, as by a pair of rubber tubes 3, only one of which 10 is shown, connected between the two sides of the mask and tanks of oxygen and a suitable anaesthetic, such as nitrous oxide. On the top of the mask is formed a flat circular portion 4 having a central opening or outlet 5, which serves 15 as the exhalatory of the mask through which the exhalant escapes.

The exhalatory controller, indicated generally by the numeral 6, has its lower end disposed in and secured around the edge of the opening 5, 20 and is so formed as to permit the patient to exhale through the outlet and to prevent air and outside gases from entering into the mask through this outlet. The controller preferably comprises a sound producing member or whistle 7, having 25 a gas duct or passage leading to a one-way valve 8, and a sensitive or micrometric adjuster 9 for varying the pressure exerted upon the valve 8 to normally keep it closed.

The whistle or sound producer 7 preferably 30 comprises a sound chamber formed between two separable members, so that it may be opened to be cleaned, one member being in the form of a convex circular cup 10, provided with a central opening 11, and an externally-threaded peripheral rim or flange 12, which engages an internally-threaded flange 13 formed on the other member 14, the latter member comprising a flat circular head on the end of an externally-threaded plug 15 having a central opening or passage 16 disposed in registry with but spaced from the opening 11. The plug 15 engages an internally-threaded socket 17, which is formed centrally in a cylindrical boss 18 so as to provide a clamp between the member 14 and the boss to grip the 45 edge of the opening 5 when assembled as shown in the accompanying drawing.

The boss 18 has a cylindrical rim 19 at its upper end providing a valve seat for the valve 8 as will be later described, and having a central 50 opening or chamber 20 communicating with the opening 16 formed in the plug 15 when the parts are assembled. Suitably supported on the boss 18, as by means of an internally-threaded rim 22 screwed on the externally-threaded shoulder 21 55

of the boss, is a tapered metal guard 23 in which openings 24 are provided to permit the escape of gas, the guard being provided with an integral top portion 25 formed with a threaded opening 26 which receives and supports the threaded end 27 of the micrometric adjuster 9. The adjuster 9 has a disk 28 provided with a knurled periphery and serving as a handle, formed at its upper end, and a tubular extension 29 at its lower end, while a central opening 30 extends through the member 9.

The valve stem 31 of the valve 8, which is provided at its lower end with a tapered valve body 32 having a recessed or concave back 33, extends through and is supported for shift movement in the opening 30 of the member 9. The valve is so disposed as to have limited axial shift movement, the valve body being shiftable into and out of engagement with its valve seat 34 comprising the upper end of the cylindrical flange 19. A coil spring 35 is disposed around the valve stem 31 and extends between the valve body 32 and the lower end of the threaded portion 27 of the adjuster 9. The tension of the spring 35 is such as to normally urge the valve body 32 into contact with its valve seat 34. The tension may be varied, however, by merely turning the knurled handle 28 of the adjuster 9; thus when the disk 28 is turned in a clockwise direction as far as it will turn the valve will be held closed regardless of the pressure inside the mask and by turning the disk in a counter-clockwise direction the tension of the spring is gradually reduced until it exerts no pressure whatsoever on the valve. To enable the operator to determine the adjustment of the spring, horizontal circumferential lines 36 may be drawn around the upper end of the valve stem 31, bearing suitable indicia, such as "O" to indicate open, "H" to indicate half closed, and "C" to indicate closed.

The device may be applied to an inhaler, as shown, by placing the boss 18 on the outer surface of the inhaler so that the receptacle 17 is disposed above the opening 5. The plug 15 is then inserted from the inside of the inhaler through the opening 5, into the receptacle 17 and screwed tightly in place, the sides of the opening 5 being firmly gripped between the member 14 and the boss 18, so that in operation no gas can escape from the inside of the inhaler except through the aperture 11 formed in the convex cup 10. When the patient exhales, the exhalant passes through the aperture 11 and thence through the sound chamber 7 and the passage-way 16, making an audible whistling noise. The pressure of the exhaled gas when it reaches the chamber 20, forces the tapered valve body 32 upward against the resistance of the spring 35, permitting the gas to escape. The anaesthetist can determine the state of anaesthesia by the

strength and rythym of the audible whistling noise produced when the patient exhales, and he can more accurately control the patient's condition by means of the micrometric adjuster provided on the controller.

5

I claim:

1. An exhalatory controller for inhalers comprising, in combination, a plug formed with a sound chamber at one end and a passage extending through said plug and communicating with said sound chamber, a member provided with a receptacle for receiving said plug and being formed with a chamber communicating with the passage in said plug and with a valve seat at the end of said chamber, a guard member mounted on said last-named member, a pressure operated valve supported by said guard member and shiftable into and out of engagement with said valve seat, and adjustable means for normally urging said valve into engagement with said valve seat. 20

2. An exhalatory controller for inhalers comprising, in combination, a plug formed with a sound chamber at one end and a passage extending through said plug and communicating with said sound chamber, a member provided with a receptacle for receiving said plug and being formed with a chamber communicating with the passage in said plug and with a valve seat at the end of said chamber, a guard member mounted on said last-named member, an adjustable member provided with a central opening and mounted on said guard member, a valve provided with a valve stem passing through and supported by the central opening in said adjustable member and with a tapered valve body shiftable into and out of engagement with said valve seat, and a spring disposed around said valve stem and extending between said valve body and said adjustable member so as to normally urge said valve into engagement with said 40 valve seat.

3. An inhaler for administering anaesthetics comprising a mask to enclose and fit over the nose of the patient, means for admitting an anaesthetic to said mask, an opening in said mask, a valve controlling said opening to permit exhalations but prevent inhalations therethrough, and an audible signal operated by the exhalations of the patient.

4. An inhaler for administering anaesthetics comprising a mask to fit over the nose of the patient, means for admitting an anaesthetic to said mask, an opening in said mask, a valve controlling said opening to permit exhalations but prevent inhalations therethrough, an audible signal operated by the exhalations of the patient, and means to adjust said valve in accordance with the character of the exhalations as indicated by the audible signal.

HAROLD V. O'CONNELL. 60
